(57) CLAIM

The ornamental design for the bullet, as shown and described.

DESCRIPTION

FIG. 1 is a perspective view of a first embodiment of the bullet of my new design;

FIG. 2 is the top view of the design of FIG. 1;

FIG. 3 is the side view of the design of FIG. 1, all side views of this embodiment of the design being identical;

FIG. 4 is the bottom view of the design of FIG. 1;

FIG. 5 is a perspective view of a second embodiment of the bullet of my new design; and,

FIG. 6 is the side view of the design of FIG. 1, all side views of the design being identical, the side views illustrate the difference between the embodiment of FIGS. 1-4, namely the length of the cylindrical section at the transition of the ogive to the bullet tip, the top and bottom views of the embodiment of FIGS. 5 and 6 are identical to the embodiment of FIGS. 1-4.
